Primary Examiner — Sheryl Lane*Assistant Examiner* — Samantha N Wood(74) *Attorney, Agent, or Firm* — Stephen J. Weyer, Esq.;
Stites & Harbison PLLC(57) **CLAIM**

The ornamental design for a tote, as shown and described.

DESCRIPTION

FIG. 1 is a perspective view taken from the top, front, and left side of the tote of the present design.

FIG. 2 is a left side elevational view thereof.

FIG. 3 is a right side elevational view thereof.

FIG. 4 is a bottom plan view thereof.

FIG. 5 is a top plan view thereof.

FIG. 6 is a front elevational view thereof; and,

FIG. 7 is a rear elevational view thereof.

The portions drawn in broken lines of the tote form no part of the claimed design.

1 Claim, 7 Drawing Sheets(56)
